UNITED STATES PATENT OFFICE.

EDWARD ARNOLD AND HENRY TEMPLETON, OF YAKIMA, WASHINGTON.

BOX COVER.

Application filed April 25, 1927. Serial No. 186,451.

This invention relates to box covers and more particularly to a detachable and adjustable box cover for use upon containers for groceries and other goods, and it has for 5 its object to provide a device of this character which will permit of the exposure of the goods to view, while at the same time the goods will be protected from contact with injurious outside elements.

10 Many kinds of groceries, such as dried fruits and bakery goods, as well as certain kinds of dry goods, are put up in containers by the manufacturers which are suitable in which to leave the goods for display and 15 inspection by customers in the stores, after the tops have been removed therefrom. Such display, however, must be made in accordance with the sanitary laws which have been passed in the various States, so that the 20 edibles, if that be the kind of goods displayed, may be kept in pure and fresh condition.

Transparent box covers heretofore used for such display of goods are non-adjustable. It is a primary object of the present 25 invention to provide an adjustable cover which can be used upon boxes of varying sizes, which can be made cheaply and at the same time comply with the requirements of the sanitary laws.

30 Further objects and advantages of the invention will be set forth in the detailed description which follows.

In the accompanying drawings:

Fig. 1 is a plan view of the cover in place 35 upon a box.

Fig. 2 is a side elevation of the same.

Fig. 3 is a vertical view in section illustrating the manner in which the sections of the cover overlap at the top and sides of the 40 box.

Fig. 4 is a perspective view of one of the outer sections, hereinafter described, and

Fig. 5 is a sectional view showing the means for holding the sections in fixed relation to 45 one another.

Like numerals designate corresponding parts in all of the figures of the drawing.

In carrying out the invention, we provide 50 a pair of frame sections 5, which are disposed at diagonally opposed corners of the box, and a pair of frame sections 6, which are disposed at the other corners of the box. Each of the sections 5 comprises a right angular frame, which fits upon a corner of the

box 4, and has a horizontal flange 7^a extending inwardly along the edge of the box, and a vertical portion 7^b extending downwardly along the outside edge of the box. A horizontal inner flange member 7^c is affixed beneath the flange 7^a and in spaced relation thereto, to provide a recess or groove for holding a pane of glass, celluloid, or other transparent material 10, in position over the top of the box. The frame sections 6 are disposed in such position as to slide beneath the frame sections 5, when the cover is being adjusted upon the box, and have parts 8^a, 8^b, 8^c which correspond to the parts 7^a, 7^b, 7^c of the sections 5. The lower edge of the vertical portion 7^b is curved upwardly 70 and inwardly to form a way or trough 9 and the lower edge of the member 8^b is offset at 11 to fit in the trough 9 and to slide therein when adjustment of the cover is being made.

A horizontal rod 12 is fastened at one end 13 upon one of the inner sections 6 and its free end extends through a projection 15 upon one of the sections 5, into a sheath or tube 14 attached to or formed in the vertical portion 7 of the outer section 5. The inner section 6 may then be slipped to the desired position and held in place by turning the set screw 16 in the projection 15, down against the rod 12. While we have illustrated the fastening means at one side only 85 of the cover, additional fastening means may be provided, if desired.

Thus it will be seen that the sections 5 and 90 6 may be so adjusted with respect to each other that boxes of widely varying sizes may be covered by the device, and that at all times the panes of transparent material 10 are disposed in overlapping relation to effectually prevent dust and dirt from getting into the box. Adjustment may be made in either longitudinal or lateral direction so that the same cover may be used upon a long or square box. Thus a box, which is slightly less in width than one of the panes of transparent material 10 and which is only slightly less in 95 length than the combined length of one of each of the sections 5 and 6, may be covered, while square or rectangular boxes of various dimensions may be covered.

100 While it is preferred to use transparent material as stated, it is manifest that the various adjustable sections may carry screen material

instead of transparent panes, if desired, where the purpose sought is to protect the fruit from insects. It is manifest that many ways may be resorted to for slidably mounting the sections with respect to each other. However, the particular way in which the metal of the frames is bent to bring about sliding engagement between them is immaterial, because, as before stated, there are many ways of accomplishing this result. Therefore it is to be understood that the invention is not limited to the precise construction set forth but that it includes within its purview whatever changes fairly come within either the terms or the spirit of the appended claims.

Having described our invention what we claim is:

1. The combination with a box having an open top side, of a cover therefor, comprising four horizontally disposed members, each of said members consisting of a transparent pane and an L-shaped frame member, said transparent pane being supported wholly from its outer side and end portions by being gripped by its companion L-shaped frame member, the inner sides and edges of said transparent pane being wholly free to lie in snug and close fitting relation to the other transparent panes, at such portions thereof as overlap, two of said L-shaped frame members having their lower edges bent to form channeled portions adapted to slidably receive the companion L-shaped members, said frame members being of such width as to extend down over and embrace the sides of the box to a considerable extent, to thereby

insure the retention of the cover upon the box.

2. The combination with a box having an open top side, of a cover therefor comprising four members, which overlap each other at their inner end and side edges, each of said members comprising a transparent pane, and a frame member associated with said pane, said frame members being of L-shape and comprising vertical webs of considerable depth adapted to fit down over the sides of the box, said frame members being provided with inturned horizontal flanges along their upper edges within which the outer sides and ends of the transparent panes are received, two of said frame members being bent to channeled formation along their lower edges to adapt them to slidably receive the vertical webs of the two companion frame members, and an offset rod secured to one of said frame members, a perforate element carried by another of said frame members through which said rod slides, and a binding means carried by said perforate element.

3. A structure as recited in claim 1, in combination with a binding means upon one of said frame members and a rigid element upon another of said frame members slidably engaged with said binding means, whereby when said binding means is tightened the frame members will be held against sliding movement with respect to each other.

In testimony whereof they affix their signatures.

EDWARD ARNOLD.
HENRY TEMPLETON.
